UNITED STATES PATENT OFFICE.

WILLIAM J. KENT, OF BROOKLYN, NEW YORK, ASSIGNOR TO REVERE RUBBER COMPANY, OF BOSTON, MASSACHUSETTS.

DESIGN FOR A HOOF-PAD.

SPECIFICATION forming part of Design No. 34,868, dated July 30, 1901.

Application filed April 25, 1901. Serial No. 57,502. Term of patent 14 years.

To all whom it may concern:

Be it known that I, WILLIAM J. KENT, a citizen of the United States, residing in the borough of Brooklyn, county of Kings, city and State of New York, have invented and produced a certain new and original Design for a Hoof-Pad, of which the following is a specification.

This design relates to hoof-pads for horses.

The new design relates to the shape and surface ornamentation of the pad.

My present design is shown in the accompanying drawings, in which—

Figure 1 is an obverse or bottom face view 15 of a pad embodying the new design, and Fig. 2 is a reverse or top face view thereof.

Referring to the drawings, let A indicate the obverse face, and B the reverse face.

C is the rear end, D the front end, and E 20 is the thin portion bounded by the outline F.

One distinctive feature of my design is a protuberance H on the bottom or obverse side of the pad. This protuberance is cone-shaped in general form, being of much less width at 25 its rear edge than the width of the pad and tapering from its rear edge a forwardly toward an apex b. The rear a is shown as slightly concave, and the sides c are shown as of convex shape, tapering outward slightly, 30 so that at d the protuberance is of its greatest width, and then tapering inwardly toward each other in gentle curves, which finally merge at the apex of the protuberance.

The protuberance H has a surface com-

posed of a plurality of longitudinally-extending tapering projections f and intermediate recesses e. It also has a border h, which is of the same general contour as the protuberance and is of considerably less downward extension from the thin portion E than the remainder of the protuberance.

The thin portion E of the pad extends upon three sides of the protuberance H and forms a broad border for the latter of less width at the rear of the pad and gradually increasing 45 in width toward the front thereof, at which point it is shown as at its greatest extension beyond the protuberance. This border is generally flat and smooth and is of much less thickness than the protuberance. 50

The reverse or top face of the pad is a plain face and has a central concavity J oppositely disposed to the protuberance H, this concavity being of approximately cone shape and having a concave rear wall i and concave converging side walls j.

The new design is of distinctive shape and of pleasing appearance.

What I claim is—

The design for a hoof-pad, substantially as 60 herein shown and described.

In witness whereof I have hereunto signed my name in the presence of two subscribing witnesses.

WILLIAM J. KENT.
